UNITED STATES PATENT OFFICE.

HENRY M. SCHADEWALD, OF PHILADELPHIA, PENNSYLVANIA.

HAIRCLOTH LOOM.

Application filed December 23, 1921. Serial No. 524,363.

To all whom it may concern:

Be it known that I, HENRY M. SCHADEWALD, a citizen of the United States, residing in the city and county of Philadelphia, State 5 of Pennsylvania, have invented a new and useful Haircloth Loom, of which the following is a specification.

In the operation of a jacquard machine in conjunction with a hair cloth loom, difficulty 10 has been heretofore experienced by reason of the loom weaving doubles, shives, mispicks and the like, caused by reason of the selector of the hair cloth loom missing and not taking up the hair.

15 To obviate the foregoing objections, I have devised a novel construction of automatically operated pawl mechanism coacting with the jacquard cylinder, whereby when the selector of the hair cloth loom misses a hair, certain mechanism will be automatically operated so as to stop the rotation of the jacquard cylinder, whereby mispicks, shives and doubles will be prevented.

It further consists of a novel construction 25 and collocation of a disk, an arm carried thereby, connections from said arm leading to a movable pawl coacting with a jacquard cylinder and connections leading from said disk to a hair cloth loom, whereby when the selector of the latter misses a hair the rotation of the jacquard cylinder will be automatically stopped.

It further consists of other novel features 30 of construction, all as will be hereinafter fully set forth.

For the purpose of illustrating my invention, I have shown in the accompanying drawings a form thereof which is at present preferred by me, since it will give in practice 35 satisfactory and reliable results, although it is to be understood that the various instrumentalities of which my invention consists can be variously arranged and organized and that my invention is not limited 40 to the precise arrangement and organization of these instrumentalities as herein shown and described.

Figure 1 represents a side elevation of a loom for weaving haircloth and its adjuncts, 45 with the novel attachments thereto embodying my invention.

Figure 2 represents a perspective view of a portion of the jacquard mechanism seen at the upper portion of Figure 1 and in Figure 55 3.

Figure 3 represents on an enlarged scale

a side elevation of Figure 2, certain of the parts being shown in section.

Figure 4 represents on an enlarged scale, 60 a portion of the pawl actuating mechanism coacting with the jacquard cylinder.

Figure 5 represents on an enlarged scale a perspective view of the haircloth feeding and picking means.

Figure 6 represents on an enlarged scale a 65 side elevation of the dagger and the hair controlling finger, the cam bar being shown in section.

Figure 7 represents a perspective view of the hair wire and dagger in detached position.

Similar numerals of reference indicate corresponding parts.

Referring to the drawings,

In carrying out my invention, which is 75 applied to a hair cloth loom of any conventional type used in conjunction with a jacquard machine, also of any conventional type, I have refrained from showing or explaining in detail the construction or mode 80 of operation of the hair cloth loom, as the same is well known and may be construed in accordance with the disclosures in Patents No. 756,334, of July 10, 1903, No. 948,370 of February 8, 1910, No. 834,000, of October 23, 1906, No. 769,790, of September 13, 1904, 85 No. 795,252, of July 18th, 1905 and No. 795,249 of July 18, 1905.

I have also refrained from explaining in detail the construction and mode of operation of the jacquard machine, as this is well known to those skilled in this art, and the present disclosure is directed to the novel coacting elements common to the loom and jacquard machine, wherein I have overcome 95 by my novel mechanism the difficulty heretofore experienced by reason of the loom weaving doubles, shives, mispicks and the like, because of the selector missing and not taking up the hair, wherein 1 designates 100 my novel construction of hair cloth loom, the same comprising a housing 2 in which the main shaft 3 is mounted carrying the tight and loose pulleys 4 and 5, and the bevel pinion 6, which is in mesh with the bevel gear 7 from which power is transmitted to the gear 8 mounted on the shaft 9, said shaft carrying the cam 10, which actuates the cam bar 11, which is provided with the pendant lug 12, coacting with the working face of the cam 10. The cam bar 11 105 has one end pivotally mounted at 12^{xx} upon 110

the arm 13, the opposite end of said cam bar being guided in the U-shaped ways 15. From the gear 8 power is transmitted to operative parts of the loom, but as those are old and form no part of the present invention, I have deemed it unnecessary to describe the same in detail.

16 designates a vertically movable rod, whose lower end is pivotally connected to 10 the dagger 17 having the angular or inverted V-shaped recess 18, which coacts with the similarly shaped lug 19 on the top of the cam bar 11, the end of said bar being provided with the slot 14 through which passes 15 the downward extension 12* of the dagger 17, said bar being pulled towards said cam 10 by means of the spring 10*. The upper end of the vertically movable rod 16 is pivoted at 20 to the arm 21, which is secured to 20 the disk or plate 22 by means of the screws or bolts 23.

The arm 21 has the upper end of the spring 24 attached thereto, the lower end of 25 said spring being attached at the point 25 to the frame 26, so that a downward tension is exerted on said arm and its adjuncts. The disk or plate 22 rotates upon the pin 27 carried by the bar 27* supported on the upright frame 26 and is provided with the curved 30 slot 28 through which projects the stationary pin or stop 29, it being apparent that said stop serves to arrest the rotary movement of said disk or plate 22 in each of its extreme positions.

35 30 designates a connection or cable which is pivotally secured at the point 31 to the outer end of the arm 21, said connection 30 passing over the roller 32, which is rotatably mounted on the bearing 33.

40 The upper end of the cable 30 is attached at the point 34 to the pawl 35, which is pivotally mounted at the point 36 in the arm 37 of the bracket 38, which is secured to the 45 jacquard machine housing 39 in any suitable manner. The pivotal point 36 of the pawl 35 is permitted to have a slight longitudinal movement or adjustment in the slot 40, as will be understood from Figures 2 and 3, and the proper position of said pawl with respect to the jacquard cylinder 41 is assured by means of the spring 42, acting in conjunction with the spring 24, whose lower end is attached to said pawl 35 and its upper end attached to the fixed point 43. The pawl 35 is provided with a recess 44, whose walls are adapted to engage the corners of the jacquard cylinder 41, over which the cards 45 of the usual construction pass in the usual manner.

60 46 designates a trough or churn for the hairs, which may be agitated in any well known manner. 47 designates the selector of picking mechanism and 48, the nipper for picking up a hair 49 which is drawn 65 across through the warp over the filling or

hair wire 50 which action gives said wire a slight downward movement.

The operation of the selector and nipper seen in Figure 5 is old in the art, and may be as disclosed in the patents heretofore referred to, hence I have deemed it unnecessary to describe the same in detail, or to describe in detail the operation of the jacquard mechanism 51 seen in Figures 2 and 3 and in the upper portion of Figure 1, which may also be of any conventional type, except to say that the cylinder 41 and its adjuncts are reciprocated in any well known manner, as by the reciprocation of the rod 52, which is suitably connected with the frame carrying the cylinder 41, it being apparent that when the parts are in the position seen in full lines in Figure 3, that each time the cylinder 41 is moved to the left in the direction of the arrow *a*, a corner as 53 of the jacquard cylinder 41 will engage the recess 44 of the pawl 35, and said cylinder will be given a one quarter rotation in the direction of the arrow *b*, which operation will continue until the pawl 35 is pulled into the position seen in dotted lines in Figure 3, out of the path of said cylinder, in which position of said pawl the rotation of said cylinder will cease, as is evident.

The mode of operation of the hair wire 50 with respect to the dagger 17 is best seen in Figures 5 and 6 and is substantially the same as that described in Patent No. 834,000, said wire 50 having the fulcrum or horizontal member 54, the depending member 55 and the horizontal eye 56 located below the lever 11, through which eye the downward extension 12* of the dagger 17 passes.

The operation is as follows:—

The rotation of the cam 10 imparts at the 105 proper intervals an up and down movement to the lever 11. When the selector 47 is actuated downwardly into the bunch of hairs in the churn 46 to pick up a hair, the nipper 48 grasps and draws said hair across 110 through the warp over the filling or hair wire 50, which gives said wire a slight downward movement, and the engagement of the eye 56 with the lower extension 12* of the dagger 17 causes said dagger to move to the 115 left of the position seen in Figure 6 in the direction of the arrow *c*. Through the rotation of the cam 10, the lever 11 will oscillate up and down and when the dagger 17 and its adjuncts are moved to the left of 120 the position seen in Figure 6 so that the recess 18 is out of the path of the lug 19, the latter will have no function and the pawl 35 will remain in its initial position seen in full lines in Figure 3 in which the 125 recess 44 will engage with a corner 53 of the jacquard cylinder 41 during its motion in the direction of the arrow *a*, thereby causing said cylinder to rotate a one-quarter turn.

In the event that the selector 47 misses a hair, the hair wire 50 will stay up causing the dagger 17 to assume the position seen in Figure 6.

5 Through the operation of the cam 10, the lever 11 with its lug 19 will rise and fall at the proper intervals, and during its upward movement, said lug will engage or interlock with the recess 18 of said dagger, 10 thereby causing the latter together with the rod 16 to move upwardly, thereby rocking the arm 21, and disk 22 on the axis 27 from the position seen in full lines in Figure 4 to the position seen in dotted lines in said 15 figure.

By this movement of the arm 21, the cable or connection 30 will be pulled downwardly in the direction of the arrow *d* seen in Figure 3, and the pawl 35 will move from the 20 position seen in full lines in Figure 3 into the position seen dotted in said figure and out of the path of the cylinder 41, thereby preventing the jacquard cylinder 41 from rotating during its movement back and 25 forth, since the recess 44 will be out of the path of a corner 53 of said cylinder.

The rotation of said cylinder will thus be automatically and instantly stopped and mispicks, shives and doubles will thereby be 30 prevented. The slot 8 in the disk 22 and the pin or abutment 29 act as stops to limit the movement of the disk 22, arm 21 and their adjuncts, and the tension of the spring 24 will hold the various parts under tension 35 in their proper positions, as is evident.

It will be seen from the foregoing that by the employment of my novel features comprising the bar 27*, the arm 21, disk 22, 40 spring 24, pin 29, cable 30, pulley 32, pawl 35, spring 42, and bracket 38 and their adjuncts common to the jacquard machine and hair cloth loom, a novel and efficient device for the purpose intended has been produced.

Having thus described my invention, what 45 I claim as new and desire to secure by Letters Patent, is:—

1. In a device of the character stated, a hair selector, a hair gripper, a hair wire actuated by the movement of said gripper 50 engaging a hair, a cam operated lever having a lug thereon, a dagger passing through one end of said lever, and having an extension adapted to be engaged by an exten-

sion of said hair wire, and a recess adapted to be engaged by said lug, a rod having its lower end pivoted to said dagger, an oscillatory arm rotatably supported, the upper end of said rod being pivoted to said arm, a rotatable jacquard cylinder, means for reciprocating said cylinder, a pawl having a recess adapted to engage a portion of said cylinder and a connection from said arm to said pawl for actuating the latter. 55

2. In a device of the character stated, a hair selector, a hair gripper, a hair wire 60 actuated by the movement of said gripper engaging a hair, a cam operated lever having a lug thereon, a dagger passing through one end of said lever and having an extension adapted to be engaged by an eye 65 movable in unison with said hair wire and a recess adapted to be engaged by said lug, a rod having its lower end pivoted to said dagger, a disk rotatably supported, an arm attached to said disk, and pivotally connected with the upper end of said rod, a spring for said arm, a stop for limiting the movement of said arm and disk, a jacquard cylinder, means for reciprocating the latter, a pawl normally in the path of said cylinder and adapted to engage a portion thereof, a connection from said arm to said pawl, 70 and a spring for said pawl.

3. In a device of the character stated, a hair selector, a hair gripper, means operated from said gripper for actuating said dagger when the gripper misses a hair, a rotary arm, a connection from said dagger to said arm, a spring for said arm, a stop for limiting the movements of said arm, a cable having its lower end engaging said arm, a pawl capable of a pivotal and longitudinal movement, a spring for said pawl, the upper end of said cable being secured to said pawl, and the latter being retained 85 in normal position by said springs, a jacquard cylinder having a portion thereof adapted to be engaged by said pawl when in normal position, whereby said cylinder 90 is rotated, and means for reciprocating said 95 cylinder. 100

HENRY M. SCHADEWALD
